UNITED STATES PATENT OFFICE.

JOHN LEWIS MILTON, OF LOUISVILLE, KENTUCKY.

MAGNETO.

Application filed January 12, 1921. Serial No. 436,740.

To all whom it may concern:

Be it known that I, JOHN LEWIS MILTON, a citizen of the United States of America, residing in Louisville, in the county of Jefferson and State of Kentucky, have invented certain new and useful Improvements in Magnetos, of which the following is a specification, reference being had to the accompanying drawings.

10 This invention relates to improvements in electric generators, more particularly to induction alternators especially adapted for use in connection with internal combustion engines.

15 I have sought to reduce the costs of production and to increase the efficiency of the class of devices to which my invention relates.

For the purpose of disclosing my invention and its scope of application, I have selected the accompanying drawings in which:—

Figure 1 is a transverse cross-sectional view of an electric generator embodying my invention, in a substantially full size scale of a machine which I have had in successful operation for a long period of time.

Figure 2 is a transverse cross-sectional view of an electric generator embodying a modification of the application of my invention, and shows the operating spring placed inside the generator.

Figure 3 is an end elevation of Figure 1 with the face member of the operating lever removed.

Figure 4 is an end elevation of Figure 1 with a starting lever added and also shows an operating part of the engine on which it is to be installed.

40 Figure 5 is a view taken along line C—C of Figure 2.

Like figures and references denote the same parts wherever they are shown.

In the drawings:—

45 1 indicates the rotor and rotor shaft constructed as a unit; 2 is a base and pole piece of magnetic material which I have shown as a unitary casting; it can be constructed of stampings where desirable.

50 The double acting torsion spring 12 em-

bodies a unique feature of my generator. It is shown enclosed in Figure 2 and exposed in Figure 1 and disposed on bearing 13 made of either magnetic or non-magnetic material. A lug 14 is made a part of said bearing and serves to engage the ends 14^a, 14^b of spring 14. A lug 15^a an extension of operating oscillating lever 15 is so correlated with the lug 14 that it will freely swing past same. It will be noted that the spring 60 ends 14^a, 14^b, also engage lug 15^a. The torsion type of spring can be so formed that as it is put in place as shown in the drawings, it will be strained so as to be under pressure i. e. it will exert pressure on the lug fixed 65 to the generator frame and without exerting pressure on the trip finger lug until the latter is moved from rest. As it moves from rest, it engages the spring already under any desired tension. When desirable, the 70 spring may be so formed as to be capable of installing without being placed under this initial tension, and just so its ends will register with either of the lugs, which may be of the same or 75 varying widths, according to results desired. While I have shown the torsion spring encircling the shaft or a bearing and shaft, its form and disposition are susceptible of many variations that will suggest themselves to 80 one skilled in the art. This is also true of the lugs; they may be dispensed with and other means provided for engaging the spring ends. A suitable device which is a 85 part of the internal combustion engine on which my generator is to be placed and which is shown in Figure 4 engages with the face 15^c of lever 15 and moves it in a clockwise direction as viewed in Figure 4.

When lever, rotor and timer cam are released, the stressed spring 12 rapidly returns these members to rest. It will be noted that this spring impels and then arrests the rotor and the parts affixed to it.

Many widely varying embodiments of my 95 invention and various applications thereof, such as will suggest themselves to those skilled in the art to which my invention relates, may be used and made without departing from the spirit and scope of my invention 100

tion. My disclosures and the foregoing descriptions are purely illustrative and are not intended to be in any sense limiting.

What I claim is:—

- 6 1. The combination of an electric generator provided with a stator and a rotor, and a mechanism for oscillating said rotor, in which a torsion spring constructed with free ends is supported by said stator, and 70
10 the free ends engage a lug fixed on the stator; also, a lug on said oscillating mechanism so as to return said rotor to a predetermined position when moved away from same and released.
- 15 2. The combination of an electric generator provided with a frame and a rotor, and a mechanism for oscillating said rotor, in which a torsion spring constructed with free 75
20 ends is supported by said frame, and the free ends engage two members, one carried on said rotor and the other one carried by said frame so as to return said rotor to a predetermined position when moved away from same and released.
- 25 3. The combination of an electrical generator provided with a lug mounted on the frame thereof, a rotor and an operating lever attached to same, with a torsion spring surrounding said rotor shaft; the ends of 80
30 which engage said lug and an extension of said lever.
- 35 4. The combination of an electric generator provided with a lug mounted thereon, a rotor and an operating lever attached to same with a torsion spring surrounding said 85
35 rotor shaft and engaging said lug and lever so as to return said rotor to a predetermined position when moved away from same.
- 40 5. The combination of an electrical generator, a rotor, a trip finger mounted thereon, a torsion spring surrounding the generator bearing and rotor shaft and a pair of 90
45 lugs, one being mounted on the generator frame and the other being a part of said trip finger.
- 50 6. The combination of an electrical generator, a rotor, a trip finger mounted thereon, a torsion spring surrounding the generator bearing and rotor shaft and a pair of lugs, one being mounted on the generator frame and the other being a part of said trip finger, and the ends of said spring being 95
55 so correlated with the lugs as to hold them in alignment when the rotor is at rest.
- 60 7. The combination of an electrical generator provided with a lug mounted thereon, a rotor with a lug attached thereto with a torsion spring surrounding said rotor shaft and engaging said lugs so as to 100
65 hold said rotor in a predetermined position when at rest.
- 65 8. In an oscillator for magnetos, a torsional spring operatively connected to a magneto shaft, stationary means for holding 105
70 said spring under initial tension, movable 110
75 means for imparting a further torsional strain to said spring, whereby the release of said spring produces an accelerated rotation of the magneto shaft, and means whereby 115
80 said spring operates as a buffer to absorb the shock of the parts as they return to normal position.
9. In an oscillator for magnetos, a torsional spring consisting of a coiled body portion terminating in oppositely extending 120
95 ends, a member extending through the coils of said body portion for supporting said spring, means for operatively connecting said spring to a magneto shaft, and means for imparting a torsional strain to said spring in either 125
100 direction, whereby the release of said spring produces an accelerated reverse rotation of the magneto shaft.
10. In a magneto, an oscillator comprising a coiled torsional spring mounted in substantially axial alinement with the magneto shaft and operatively connected therewith, 130
105 means for holding said spring in normal position, means for imparting a torsional strain to said spring, so that the release of said spring produces an accelerated rotation of the magneto shaft, and means whereby 135
110 said spring acts to absorb the shock of the parts as they return to normal position.
11. In a magneto, an oscillator comprising a coiled torsional spring mounted in substantially axial alinement with the magneto shaft and operatively connected therewith, 140
115 means for holding said spring in normal position, means for imparting a torsional strain to said spring in either direction, so that release of said spring produces an accelerated rotation of the magneto shaft, and means whereby 145
120 said spring acts to absorb the shock of the parts as they return to normal position from either direction.
12. In a magneto, an oscillator provided with a torsional spring consisting of a coiled body portion having a projecting end, 150
125 a member extending through the coils of said body portion for supporting said spring, means for operatively connecting said spring to the magneto shaft, a stop for said projecting end of the spring, and means connected with the magneto shaft for moving said end of the spring away from said stop, whereby release of the spring causes 160
130 accelerated rotation of the magneto shaft, said spring acting to absorb the shock of the returning parts by engaging said stop.
13. In a magneto, an oscillator having a coiled torsional spring with projecting ends, a stationary stop for each end of the spring, and means connected with the magneto shaft for moving either end of the spring away 165
135 from its associated stop, whereby release of the spring causes accelerated rotation of the magneto shaft, the actuated end of the 170
140 spring acting to absorb the shock of the re-

turning parts by engaging the associated stop.

14. In a magneto oscillator, a torsional spring consisting of coils arranged to form a cylindrical body portion and terminating at one end in a projection, means for operatively connecting said spring to a magneto shaft, a stop for said projecting end of the

spring, and means for moving said end of the spring away from said stop, whereby ¹⁰ release of the spring causes accelerated rotation of the magneto shaft.

In testimony whereof, I have hereunto set my hand this 10th day of January, 1921.

JOHN LEWIS MILTON.
